GAMEBOARD

Harry X. Ford, Walnut Creek, Calif.

Application December 31, 1958, Serial No. 53,990

Term of patent 3½ years

(Cl. D34—5)

The single drawing figure is a plan view of a gameboard, showing my new design.

The gameboard is of conventional thickness.

The drawing is lined to illustrate contrasts of color.

I claim:

The ornamental design for a gameboard, as shown and described.
